UNITED STATES PATENT OFFICE

160,067

COMBINED FAUCET AND SINK

Charles Kepler Brown, Jr., Fairmont, W. Va.

Application October 6, 1947, Serial No. 141,774

Term of patent 14 years

(Cl. D4—2)

To all whom it may concern:

Be it known that I, Charles Kepler Brown, Jr., a citizen of the United States, a resident of Fairmont, West Virginia, have invented a new, original, and ornamental Design for a Combined Faucet and Sink, of which the following is a specification, reference being had to the accompanying drawing, forming a part hereof.

Figure 1 is a plan view of a combined faucet and sink, showing my new design;

Figure 2 is a front elevation of Figure 1; and

Figure 3 is a side elevation of Figure 1.

Fig. 4 is a top perspective view thereof.

I claim:

The ornamental design for a combined faucet and sink, as shown:

CHARLES KEPLER BROWN, JR.
